United States Patent Office.

WILLIAM E. BEMAN, OF PORTLAND, MAINE.

Letters Patent No. 77,348, dated April 28, 1868.

IMPROVEMENT IN JIB-BOOMS.

The Schedule referred to in these Letters Patent and making part of the same.

TO ALL WHOM IT MAY CONCERN:

Be it known that I, WILLIAM E. BEMAN, of Portland, in the county of Cumberland, State of Maine, have invented a new and useful Improved Jib-Boom; and I hereby declare the following to be a full, clear, and exact description thereof, which will enable others to make and use my invention, reference being had to the accompanying drawings, forming part of this specification, in which is shown a side elevation of same.

When merchant-vessels are in a crowded harbor, economy of space is a matter of great importance, and ship-masters are required, by the regulations of many of these ports, to ship the yards and booms, which would otherwise overhang the quay and water, and obstruct the transportation of merchandise or the passage of other vessels to and from their places at the wharf.

My invention has special reference to an easy and simple method of unshipping the jib-boom. This operation, as at present performed, requires the labor of a number of men for a length of time varying from two hours to half a day; for it is necessary to remove all the stays from the boom and draw it through the bees upon the deck, where it occupies much valuable space. By the use of my device, two men can perform the work in much less time, and, moreover, the boom, when on board the vessel, is so placed as not to interfere with the various operations on deck.

The drawings may be readily explained. At the outer end of the bowsprit, I place a cap, *a*, through which the jib-boom passes when in place, as at *b*. This cap is so arranged as to open upon a hinged joint, *d*, in the side of the same, as shown more fully at *c*. It is secured, when shut, by a pin, *h*, passed through corresponding holes *e e* in the upper and lower portion of it, or by any convenient device.

The jib-boom *b* is secured at its inner end, by a horizontal joint, to the bowsprit of the vessel, or to a step bolted thereto, seen at *f*. When it is necessary to ship this boom, the pin *h* is withdrawn, the cap thrown up, and by the application of a block and tackle the boom may be drawn up to a perpendicular position, and secured as is shown at *b'*. It is not at all necessary to remove the stays and rigging, as is the case with the ordinary boom, for it passes between those attached to the bowsprit on either side of the same, and carries up with it those fastened to the boom itself.

I am aware of the patent of D. W. Norcross, December 27, 1864, No. 45,625, on a boom or gaff-joint, at the junction of the sail boom or gaff to the mast, and I do not claim a boom or gaff-joint with a triple motion, nor a swivel with a bracket or grooved rail, nor combining with a boom or gaff a joint universal. The purpose and structure of this invention are different from mine. My invention could not be applied to a boom or gaff in its connection with a mast, because it admits of no lateral motion, but is intended solely for the application herein shown, viz, for a jib-boom thus connected with the bowsprit, for the purpose of obviating the inconvenience of shipping the jib-boom in on deck or out, through the ordinary caps, as customary.

What I claim as my invention, and desire to secure by Letters Patent, is—

The jib-boom *a*, when hinged to the bowsprit in the manner herein set forth; and for the purpose specified.

WILLIAM E. BEMAN.
